JOSEPH A. COSTELLO, OF CLEVELAND, OHIO, ASSIGNOR TO CLEVELAND CAR SPECIALTY COMPANY, OF CLEVELAND, OHIO, A CORPORATION OF WEST VIRGINIA.

CARLINE.

1,299,916.

Specification of Letters Patent.

Patented Apr. 8, 1919.

Application filed September 25, 1918. Serial No. 255,545.

To all whom it may concern:

Be it known that I, JOSEPH A. COSTELLO, a citizen of the United States, residing at Cleveland, in the county of Cuyahoga and 5 State of Ohio, have invented a new and useful Carline, of which the following is a specification.

This invention relates to a pressed steel carline adapted for use as a transverse member of a car-roof-frame and readily pressable by means of dies from a single steel plate or sheet of suitable dimensions, and this invention pertains more especially to a metal carline having a body which is not 10 only in the form of a trough adapted to be interposed endwise between the two laterally spaced side plates of a car-roof-frame and has two laterally and outwardly projecting longitudinal flanges arranged at the 15 top of opposite sides respectively and extending from end to end of said body but has two end flanges which are formed at opposite ends respectively and project downwardly from said body and extend 20 transversely of the carline and laterally of and outwardly beyond the sides of said body and to the aforesaid longitudinal flanges.

One object of this invention is to produce 25 an inexpensive carline of the character indicated which is more especially adapted to be interposed wholly between and to adequately brace the hereinbefore mentioned side plates.

Another object is to have the transverse end flanges of said carline extend far enough below the hereinbefore mentioned body to enable the formation, in said flanges below the bottom of said body, of holes for 35 the reception of rivets employed in securing the carline to the hereinbefore mentioned side plates, so as to avoid any weakening by said holes of the upper portions of said flanges, and so as to facilitate riveting of 40 said flanges to said side plates.

Another object is to efficiently brace the inner side of each end portion of each transverse end flange of my improved carline along the outer side edges and from top to 50 bottom of said portion of said flange, and consequently to brace said flange not only at points spaced outwardly from the sides of the hereinbefore mentioned body but at points lower than the rivet-holes formed in 55 said flange at points below said body.

Another object is to brace each end portion of each transverse end flange by a substantially triangular laterally facing brace which is formed between said transverse flange and the adjacent longitudinal flange 60 and integral with said flanges and has an inclined bottom edge extending substantially straight to said longitudinal flange from the bottom edge of said transverse flange.

Another object is not only to have the 65 hereinbefore-mentioned body substantially uniform in width from end to end and to have each end portion of each longitudinal flange gradually enlarged in width toward the adjacent transverse end flange and to 70 have said transverse flange extending laterally of and outwardly from said body as far as the widest portions of the adjacent end portions of the longitudinal flanges extend from said body, but to have the brace-forming 75 members for said transverse flange diverge toward said transverse flange so that the inclined edges of said brace-forming members converge upwardly and so that said brace-forming members are contoured 80 and arranged as required to efficiently brace said transverse flange against all strains or stresses to which it may be subjected.

Another object is to have my improved 85 carline strong enough in its end portions and to have said end portions so contoured that, when said carline is interposed between and secured to the laterally facing members of angle bars arranged to form the side plates of a car-roof-frame, each end 90 portion of the carline efficiently braces the laterally facing member of the adjacent side plate during racking or weaving of a railway car having said car-roof-frame.

With these objects in view this invention 95 consists in such peculiarities in the contour of the end portions of the carline and in such relative arrangement of the parts, as are hereinafter described in this specification, pointed out in the claims, and illustrated in the accompanying drawings.

In said drawings, Figure 1 is a top plan 105 of a carline embodying my invention and shows the carline applied to the side plates of a car-roof-frame. Fig. 2 is a vertical section taken along the line 2—2, Fig. 1. Fig. 3 is a vertical section taken along either line 3—3, Fig. 2, looking outwardly. Fig. 4 is a horizontal section taken along the line 4—4, Fig. 3, looking upwardly.

My improved carline is adapted for use as a transverse member of a car-roof-frame comprising two laterally spaced substantially parallel metal side plates each of which is shown as consisting of a substantially horizontal angle-bar A arranged so as to have one member 6 thereof facing laterally and forming the inner side of the side plate formed by said bar.

10 Arranged wholly between the side plates A is a metal carline embodying my invention and having a body B which is U-shaped in cross-section and consequently in the form of a trough. Said body B is shown interposed endwise between the laterally facing members 6 of the side plates A. The body B is provided at the top of each side thereof with a laterally and outwardly projecting longitudinal flange 7 extending longitudinally and from end to end of said body. The body B is provided at each of its ends with an end flange 8 extending transversely of the carline.

The body B is preferably substantially uniform in width from end to end, and each end portion of each longitudinal flange 7 is gradually enlarged in width, as at 9, toward the adjacent transverse flange 8. The flanges 7 and 8 are shown integral with the body B.

30 Each transverse flange 8 forms a U-shaped abutment for the inner side of the laterally facing member 6 of the adjacent side plate and has its outer face arranged therefore opposite and next said side of said member 35 of said side plate and is attached to said side plate as will hereinafter appear. Each transverse flange 8 is shown arranged wholly between the top and bottom of the inner side of the adjacent side plate and preferably 40 measures considerably more horizontally than vertically.

The transverse flanges 8 are shown extending laterally of and outwardly from the body B as far as the widest portions of the 45 end portions of the longitudinal flanges 7 extend from said body. The central portion of each transverse flange 8 connects with and projects downwardly from the adjacent end of the bottom of the body B. Each end portion of each transverse flange 8 extends above the central portion of said flange and connects at its upper end with the adjacent end of the adjacent longitudinal flange 7 and also connects with the adjacent side of the 50 body B. Preferably each end portion of each transverse flange 8 extends as far below as above the bottom of the body B.

Each end portion of each transverse flange 8 is provided at a point lower than the bottom of the body B with a rivet-hole 10 shown occupied by a rivet C employed in securing said flange, and consequently the carline, to the laterally facing member 6 of the adjacent side plate A. Not unimportant is the 65 extension of the end portions of each trans-

verse flange 8, as shown, far enough below the body B to enable the formation, in said flange below the bottom of said body, of the rivet-holes 10 of the flange, so as to avoid any weakening by said flange above said bottom, and so as to facilitate riveting of said portions of said flange to the adjacent side plate. 70

Arranged at the inner side of each end portion of each transverse flange 8, between 75 said portion of said flange and the adjacent end portion of the adjacent longitudinal flange 7, is a substantially triangular brace-forming member 12 which faces laterally of the carline and extends endwise of said longitudinal flange at the outer longitudinal edge of said longitudinal flange and up and down the adjacent side edge of said transverse flange. Preferably each brace-forming member 12 is integral with the adjacent 80 longitudinal flange 7 and with the adjacent transverse flange 8 and has an inclined bottom edge 13 extending diagonally between said flanges and substantially straight to said longitudinal flange from the bottom 85 edge of said transverse flange. 90

By the construction hereinbefore described it will be observed that my improved carline is shown as arranged wholly between and adequately braces the laterally facing members 6 of the side plates A, that the extension of the central and end portions of each transverse flange 8 of the carline as far below the bottom of the body B as said end portions extend above said bottom renders 100 the U-shaped abutment formed by said flange capable of affording a large lateral bearing to the inner side of the adjacent side plate, and that each brace-forming member 12 extends to the lower extremity of the contiguous 105 end portion of the adjacent transverse flange 8 and consequently extends not only below the bottom of the body 8 but lower than the rivet-hole 10 formed in said portion of said transverse flange at a point lower 110 than said bottom and where said flange can be conveniently riveted to the laterally facing member 6 of the adjacent side plate. It will also be observed that the brace-forming members 12 of each end portion of the 115 carline, by their extension as far below as above the bottom of the body B and their divergence toward the contiguous transverse flange 8 and the convergence of their inclined edges 13 upwardly from said flange, 120 as shown in Fig. 3, have the dimensions, contour and arrangement required to constitute simple and efficient means whereby said flange is adequately braced against all strains or stresses to which it may be subjected, and I would here remark that, in a 125 railway car having a car-roof-frame comprising the hereinbefore mentioned side-plate-forming angle-bars and carlines embodying my invention, the laterally facing 130

members of said bars are efficiently braced during racking or weaving of the car.

What I claim is:—

What I claim is:

1. A metal carline having a body which extends longitudinally of the carline and has two laterally and outwardly projecting longitudinal flanges arranged at the top of opposite sides respectively and extending from end to end of said body and is provided at each of its ends with a flange extending transversely of the carline, said transverse flange being larger horizontally than vertically and having its central portion connecting with and projecting downwardly from the bottom of said body and having each end portion thereof extending above said central portion and below said bottom and connecting with the adjacent longitudinal flange and with the adjacent side of said body, and two brace-forming members arranged at the inner side of opposite end portions respectively of said transverse flange and facing laterally of the carline, each of said brace-forming members extending up and down the adjacent outer side edge of said transverse flange and endwise of the adjacent longitudinal flange and being integral with said flanges, and each end portion of said transverse flange being provided with a rivet-hole at a point which is above the bottom edge of the flange and below the aforesaid body.
2. A metal carline having a body which extends longitudinally of the carline and has two laterally and outwardly projecting longitudinal flanges arranged at the top of opposite sides respectively and extending from end to end of said body and is provided at each of its ends with a flange extending transversely of the carline, said transverse flange having its central portion connecting with and projecting downwardly from the bottom of said body and having each end portion thereof extending above said central portion and connecting with the adjacent longitudinal flange and with the adjacent side of said body, and two substantially triangular brace-forming members arranged at the inner side of opposite end portions respectively of said transverse flange and facing laterally of the carline, each of said brace-forming members extending up and down the adjacent longitudinal flange and being rigid with said flanges, and the bottom edges of the brace-forming members of each end portion of the carline converging upwardly from the adjacent transverse flange.
3. A metal carline having a body which extends longitudinally of the carline and has two laterally and outwardly projecting longitudinal flanges arranged at the top of opposite sides respectively and extending from end to end of said body and is provided at each of its ends with a flange extending transversely of the carline and having an inclined bottom edge extending substantially straight from the bottom edge of said transverse flange upwardly and inwardly to said longitudinal flange.
4. A metal carline having a body which extends longitudinally of the carline and has two laterally and outwardly projecting longitudinal flanges arranged at the top of opposite sides respectively and extending from end to end of said body and is provided at each of its ends with a transverse flange which has its central portion projecting downwardly from the bottom of said body and has each end portion thereof extending above said central portion and as far below as above said bottom and connecting with the adjacent longitudinal flange and with said body, and two brace-forming members arranged at the inner side of opposite end portions respectively of and diverging toward said transverse flange and facing laterally of the carline, each of said brace-forming members extending up and down the adjacent transverse flange and endwise of the adjacent longitudinal flange and being rigid with said flanges, and the bottom edges of the brace-forming members of each end portion of the carline converging upwardly from the adjacent transverse flange.
5. A metal carline having a body which extends longitudinally of the carline and is U-shaped in cross-section and provided at each of its ends with a flange extending transversely of the carline and has two laterally and outwardly projecting longitudinal flanges arranged at the top of opposite sides respectively and extending from end to end of said body, the aforesaid transverse flange being larger horizontally than vertically and having its central portion projecting downwardly from said bottom and having each end portion thereof extending above said central portion and as far below as above said bottom and connecting with the adjacent longitudinal flange and with said body, and two brace-forming members arranged at the inner side of opposite end portions respectively of and diverging to

- ward said transverse flange and facing laterally of the carline, each end-portion of said transverse flange being provided with a rivet-hole at a point lower than the afore-
5 said bottom, and each of said brace-forming members being rigid with said transverse flange and with the adjacent longitudinal flange and extending as far below as above said bottom.
- 10 6. The combination, with two laterally spaced side plates of a car-roof-frame, of a metal carline having a body which extends between the upper portions of said side plates and has two laterally and outwardly
15 projecting longitudinal flanges arranged at the top of opposite sides respectively and extending to the ends of said body and is spaced upwardly from the bottom of said side plates and provided at each of its ends
20 with a transverse flange which is larger horizontally than vertically and arranged opposite the inner side of the adjacent side plate and has its central portion projecting downwardly from the bottom of said body and
25 has each end portion thereof extending above and below said bottom and connecting with the adjacent longitudinal flange and with said body, and two brace-forming members arranged at the inner side of opposite
30 end portions respectively of said transverse flange, each of said brace-forming members being rigid with said transverse flange and with the adjacent longitudinal flange, and said transverse flange being secured to the
35 adjacent side plate at points between the lower portions of said brace-forming members and lower than the aforesaid body.
7. The combination, with two laterally spaced side plates of a car-roof-frame, of a
40 metal carline having a body which extends longitudinally of the carline and is U-shaped in cross-section and interposed endwise between the upper portions of said side plates and provided at each end with a transverse
45 flange contoured and arranged to form a U-shaped abutment for the inner side of and secured to the adjacent side plate and has two external longitudinal flanges arranged at the top of opposite sides respectively and
50 extending from end to end of said body and

having each end portion thereof enlarged in width toward the adjacent side plate, and said transverse flange having its central portion projecting downwardly from the bottom of said body and having each end portion thereof extending below and above said bottom and connecting with the adjacent longitudinal flange, and two brace-forming members arranged at the inner side of opposite end portions respectively of said transverse flange and diverging toward the adjacent side plate, each of said brace-forming members connecting with said transverse flange and with the adjacent longitudinal flange and extending as far below as above the aforesaid bottom.

8. The combination, with two laterally spaced angle-bars each having one member thereof forming the inner side of a side plate of a car-roof-frame, of a metal carline having a body which extends longitudinally of the carline and has two outwardly projecting longitudinal flanges arranged at the top of opposite sides respectively and extending from end to end of said body and is interposed between the upper portions of said angle-bars and provided at each end with a transverse flange facing and forming an abutment for the adjacent angle-bar, said transverse flange being larger horizontally than vertically and having each end portion thereof extending below said body and to the adjacent longitudinal flange, and two brace-forming members arranged at the inner side of opposite end portions respectively of said transverse flange, each of said brace-forming members connecting with said transverse flange and with the adjacent longitudinal flange and having its lower portion arranged lower than the aforesaid body, and each transverse flange being riveted at points lower than said body, to the adjacent angle-bar.

In testimony whereof I sign the foregoing specification in the presence of two witnesses. 95

JOSEPH A COSTELLO.
